VENDING MACHINE CABINET

Clare E. Hodgman, Mamaroneck, N.Y., assignor to The Vendo Company, Kansas City, Mo., a corporation of Missouri

Application November 24, 1958, Serial No. 53,485

Term of patent 14 years

(Cl. D52—3)

Fig. 1.

Fig. 2.

Fig. 3.

Fig. 1 is a perspective view of a vending machine cabinet, showing my new design;

Fig. 2 is an enlarged, fragmentary, detailed, sectional view thereof taken on line 2—2 of Fig. 1; and

Fig. 3 is a fragmentary, front elevational view of that portion through which Fig. 2 is taken.

The side of the vending machine not shown is substantially the same in appearance as the side shown and the rear is unadorned.

The dominant features of my new design are shown in solid lines in the drawing.

I claim:

The ornamental design for a vending machine cabinet, as shown and described.
